UNITED STATES PATENT OFFICE.

EMIL BRAUN, OF MOULTON, TEXAS.

POISON-DISTRIBUTER.

SPECIFICATION forming part of Letters Patent No. 628,920, dated July 18, 1899.

Application filed April 5, 1899. Serial No. 711,866. (No model.)

To all whom it may concern:

Be it known that I, EMIL BRAUN, a citizen of the United States, residing at Moulton, in the county of Lavaca and State of Texas, have 5 invented a certain new and useful Poison-Distributer, of which the following is a specification.

My invention relates to that class of machines used for distributing poisons in the 10 form of a powder upon plants for the purpose of killing insects which infest the plants, the object of the invention being to generally improve the construction and operation of that class of machines.

15 With this object in view my invention consists in the improved construction, arrangement, and combination of parts hereinafter fully described and afterward specifically pointed out in the appended claims.

20 In order to enable others skilled in the art to make and use my invention, I will now proceed to describe its construction and operation, reference being had to the accompanying drawings, forming part hereof, in which—

25 Figure 1 is a plan view of a machine constructed in accordance with my invention, the tongue or pole being broken away to shorten the figure. Fig. 2 is a view in elevation of the right-hand side of the machine. Fig. 3 is

30 a transverse vertical sectional view taken on the plane indicated by the dotted line 3 3 of Fig. 2 looking in the direction of the arrows. Fig. 4 is a detail sectional view taken on the plane indicated by the dotted line 4 4 of Fig.

35 2 looking downward, as indicated by the arrows. Fig. 5 is a transverse vertical view of the powder-hopper and blower-pipe. Fig. 6 is a detail perspective view of the stirring mechanism removed from the hopper. Fig.

40 7 is a detail perspective view of the upper part of the powder-hopper and its hinged hood. Fig. 8 is a detail vertical sectional view on the plane indicated by the dotted line 8 8 of Fig. 1. Fig. 9 is a detail vertical sectional view on the plane indicated by the dotted line 9 9 of Fig. 1. Fig. 10 is a detail vertical sectional view on the plane indicated by the dotted line 10 10 of Fig. 1. Fig. 11 is a detail vertical sectional view on the plane indicated

45 by the dotted line 11 11 of Fig. 5.

Like numerals of reference mark the same

parts wherever they occur in the various figures of the drawings.

Referring to the drawings by numerals, 12 indicates an ordinary cart frame or body 55 mounted on wheels 13 and 14, the former being an ordinary wheel and serving only as a support for the body and the latter the driving-wheel of the distributing mechanism. The traction-wheel 14 is provided with a large 60 gear-wheel 15, formed with a lateral or circular angular iron flange 16, the gear-wheel being secured to the traction-wheel by means of clamp-bars 17 outside the wheel and bolts 18 securing them to the circular flange. The 65 gear-wheel 15 meshes with a pinion 19, mounted loosely on the main driving-shaft 20, journaled in pillow-blocks 21 and 22, mounted on the cart-body. The gear-wheel 15 and pinion 19 are protected by a sheet-metal guard 23, 70 secured to the frame of the body. The hub of the pinion 19 is extended at 24 to form one member of a ratchet-clutch, the other member being an oppositely-toothed sleeve 25, mounted to slide but held against turning on 75 shaft 20 and normally held in engagement with the member 24 by means of a spring 26. By this means when the cart is drawn forward the shaft 20 is rotated; but when the cart is backed the teeth of the clutch members slip over each other and the shaft remains still. A shifting-lever 27, pivoted to an extension of the pillow-block 21, serves to withdraw the clutch-sleeve 25 and throw the 80 distributing mechanism out of gear whenever 85 desired during the forward movement of the cart.

A gear-wheel 28 on the shaft 20 meshes with a pinion 29 on a shaft 30, journaled in pillow-blocks 31 and 32, mounted on the cart-body, 90 which shaft 30 carries a belt-pulley 33, connected by a belt 34 with a small pulley 35 on the shaft 36 of a fan or blower 37, the blast from which is discharged through a pipe 38, passing under a hopper 39 and provided beyond the hopper with two elbows 40 and 41, the latter pivotally mounted on its transverse axis and carrying at the extremity of its longitudinal arm a Y-shaped fitting 42, to the horizontally-diverging arms of which are attached distributing-nozzles 43. These nozzles are cut off at their outer ends at an in-

elation of about forty-five degrees, as shown in detail at 44 in Fig. 9, and a thin plate 45 is secured to the tops and bent down over the inclined ends, leaving small spaces between 5 the inclined ends and the plates to spray or scatter the powder when discharged.

A sprocket-wheel 46 on shaft 20 connects by means of a drive-chain 47 with a sprocket-wheel 48 on a horizontal shaft 49, journaled 10 in arms 50, projecting above the top of hopper 39. The drive-chain passes under rollers 51 and 52, journaled in standards 53, mounted on the cart-body, passing between said standard and guided thereby.

15 The hopper is provided with a hood 54, hinged at one side to an arm 54^a, projecting above the hopper, and provided at its opposite side with a spring-latch 55 to engage a keeper 56, secured to the side of the hopper 20 to hold it down when the distributor is in operation.

The hopper 39 terminates at its lower end in funnel shape, and in this funnel are arranged stirrer-blades 57, secured to the lower 25 end of a vertical shaft 58, journaled in the hopper and driven through the medium of a bevel-pinion 59, meshing with a similar pinion on the horizontal shaft 49.

30 The funnel of the hopper 39 terminates at its lower end in a short pipe 60, secured at its lower end in a fitting consisting of a nipple 61 on a plate 62. A similar but reverse fitting, consisting of a plate 63 and nipple 64, is secured below the fitting first named by 35 bolts 65, carrying separators 66, leaving a space between the plates 62 and 63, in which is pivotally mounted on a bolt 67 a cut-off or trap-door 68, connected at its outer end with a rod 69, extending to and connected with a hand-lever 70, pivoted to the cart-body and provided with a spring-pawl 71, engaging a curved rack 72, secured to the body. A short 40 nozzle 73 depends from the nipple 64 into the blower-pipe 38, said nozzle being cut off at its lower end at an inclination, as at 74, and arranged with its longest size toward the blower. 45

Upon the Y-fitting 42 is a ring 75, from which projects upward an arm 76, pivotally connected at its outer end with the rear end 50 of a rod 77, which is pivotally connected at its front end with a hand-lever 78, pivotally mounted on the cart-body and provided with a spring-pawl 79, engaging a curved rack 80, secured to the body.

55 The hopper 39 is supported by uprights on each side, each set consisting of a forward but rearwardly-inclined bar 81 and a rear forwardly-inclined bar 82, a bolt 83 passing through the upper ends of the bars of each 60 pair into the hopper. The bars 81 and 82 of each set are further secured together and to the hopper by a bolt 84, which passes through a clamp-bar 85 on each side and into the hopper.

65 The cart is provided with a suitable spring-supported seat 86, positioned within easy reach of the hand-levers, and with ordinary

tongue or pole 87, doubletree 88, and single-trees 89.

The construction of my improved machine 70 will be readily understood from the foregoing description, and in operation the poison in form of powder will pass down out of the hopper 39 into the blower-pipe 38 and through this pipe and the nozzle 43 will be sprayed 75 upon two adjacent rows of plants. The nozzle 73 prevents the powder from being blown back into the hopper, and the elevation at which the powder is delivered may be regulated by raising or lowering the nozzle 43 80 by means of hand-lever 78 through the medium of the rod 17 and arm 76. The amount of powder delivered is governed by the cut-off or trap-door 68, operated by hand-lever 70 through the medium of rod 69. 85

The distributing mechanism is only operated when the cart moves forward and can be thrown out of gear at any time by the clutch-shifting lever, as before described.

All the parts of the machine are simple in 90 construction, their number is limited to the minimum requisite for proper operation, their arrangement is simple, they are not liable to breakage or disarrangement from ordinarily careful use, and may be assembled or separated by ordinary unskilled labor with a 95 wrench and screw-driver.

Having thus fully described my invention, what I claim as new, and desire to secure by Letters Patent of the United States, is— 100

1. In a machine for distributing pulverized poison, the combination with a blower and a hopper, of a pipe leading from the blower, a pipe leading from the hopper to the blower-pipe, two elbows in the blower-pipe forming 105 a reverse bend, the last elbow having one of its arms transversely placed and pivoted in the first elbow, nozzles extending from its final longitudinal arm, and an arm, rod, hand-lever, and curved rack for adjusting the elevation of the nozzles, substantially as described.

2. In a machine for distributing pulverized poison, the combination with the blower and delivery pipe of an elbow therein pivoted on 115 the transverse axis of its inner arm, a pipe leading rearwardly from its final longitudinal arm, a Y-fitting in said pipe, branch pipes in the diverging arms of said fitting, spraying-nozzles at the extremities thereof, and means 120 for adjusting the inclination and elevation of the first-named pipe, substantially as described.

3. In a machine for distributing pulverized poison, a hopper terminating at its lower end in a funnel, a casting consisting of a flat plate and an upwardly-projecting nipple connecting with the funnel, a like casting consisting of a plate below the former plate and a nipple leading toward the blower-pipe, separators 125 between the plates, a cut-off door pivoted in the space thus formed, and a rod, hand-lever and curved rack for operating the cut-off, 130 substantially as described.

4. In a machine for distributing pulverized poison, the combination with the cart-body, of two sets of uprights erected thereon, each set consisting of a forwardly and a rearwardly inclined bar having registering holes in the upper ends, a powder-hopper arranged between said sets of uprights, a bolt passing through the ends of each set into the shell of the hopper, a clamp-plate grasping the edges of each set, a short distance below the top, and a bolt passing through each clamp-plate into the shell of the hopper, substantially as set forth.

5. In a machine for distributing pulverized poison, the combination with the cart-frame, of a main transverse shaft driven from one of

the traction-wheels, a pair of standards mounted on said cart-frame, upper and lower rollers journaled between the standards, a hopper, a vertical shaft therein carrying stirrer-blades, 20 a horizontal shaft at the top of the hopper geared to the vertical shaft, a sprocket-wheel on said shaft, a sprocket-wheel on the main transverse shaft, and a drive-chain connecting the two sprocket-wheels, and passing between the standards in contact with the rollers, substantially as described.
